UNITED STATES PATENT OFFICE.

CHESTER L. LYNCH, OF SEATTLE, WASHINGTON, ASSIGNOR OF ONE-HALF TO JOHN N. SHAW, OF SEATTLE, WASHINGTON.

ELECTRICALLY-OPERATED CROSSING-SIGNAL.

1,261,251.

Specification of Letters Patent. Patented Apr. 2, 1918.

Application filed September 19, 1916. Serial No. 121,000.

To all whom it may concern:

Be it known that I, CHESTER L. LYNCH, a citizen of the United States, residing at Seattle, in the county of King and State of Washington, have invented certain new and useful Improvements in Electrically-Operated Crossing-Signals, of which the following is a specification.

This invention relates to electrically operated signaling systems, and is designed to regulate signal devices such as shown and described in my co-pending application, Serial No. 104,842, filed June 21, 1916.

The object of the present invention is the perfecting of a system of electrically actuated signal devices which are used at street intersections for regulating traffic.

To these ends, I provide, first, means under the control of a local traffic officer for regulating "stop" and "go" signals for intersecting streets, selectively, said means being also applicable to the regulation of emergency signals and employing a number of normally open primary electric circuits; and, second, a series of secondary normally open circuits which, upon being closed through the office of another circuit operable from a remote place, causes the referred to secondary circuits to serve instead of the original primary circuits which are rendered inoperative with respect to the traffic officer.

A further object is to provide an audible signal, as a siren, that may be caused to sound a warning at the will of the traffic officer and that is controlled by switch apparatus whereby a warning will be automatically sounded thereby prior to the coincidental displaying of all of the stop signals on any crossing.

With the above objects in view, the invention consists in the novel arrangement, adaptation and combination of signals and the controlling circuits therefor, as will be more clearly hereinafter described and claimed.

In the accompanying drawings, Figure 1 is a view partly in section and partly in elevation of my signaling apparatus as it may appear when secured to a lamp post on one corner of a street crossing;

Fig. 2 is a view in perspective of a visual fire signal; and

Fig. 3 is a diagrammatic view of circuits controlling the operations of my signaling apparatus.

Referring to the drawings throughout which like reference numerals indicate like parts, the numeral 10 indicates a signal box of the type illustrated in my co-pending application hereinbefore referred to, the signal box being secured to a lamp post 9 and provided with a transverse shaft 11 having an L-shaped semaphore secured thereto. The semaphore comprises two arms 12 and 13 disposed substantially at right angles to each other and having inscribed thereon the words "Go" and "Stop" respectively, or equivalent signals, the stop signal arm 13 preferably being longer and heavier than the go signal arm 12 so that it will normally hang in a vertical position due to the force of gravity.

The outside of the housing 10 is provided with a shield 14 to normally protect the vertical arm of the semaphore and the shaft 11 is provided interiorly of the box with a sector 15 to which is secured a cable 16 that connects with the top end of a magnet bar 17 disposed within a solenoid 18 so that when the solenoid is energized the semaphore will be pulled downwardly and caused to display the stop signal as shown in Fig. 1.

20 is a siren that is secured to a lamp post 9 or other support for use as an emergency signal and 21 is a triangularly shaped fire signal box having a lamp 22 disposed inside thereof and having the word "Fire" inscribed on two of its transparent sides, so that such word will be visible from two sides and will show only when the lamp 22 is lighted. This may be accomplished by providing ground glass panels in the box 21 and painting the word "Fire" in black letters on the inside surface of the panels.

The signal boxes 10 are ordinarily installed on each of the four corners of a crossing, as indicated by broken lines X in Fig. 3, in such manner that the extended semaphores thereof will be visible to vehicles approaching from four directions on the right-hand sides of the respective streets, and are connected with electrical circuits, see Fig. 3, so that either the diagonally opposite signals or all of the signals may be operated at the same time.

When installed as above described, one terminal of a source of electrical current, as a battery B, is connected by an electric circuit wire 23 with the solenoid in the signal box 10 on each corner of a crossing and with

the siren 20, which may be located at any convenient or suitable place. The other terminal of the battery B is connected by a circuit wire 24 with contact blades 28, 29, 30, 5 31, 32, 33, 34, 35 and 36 which blades each have counterpart blades 28¹ to 36¹ respectively, and are disposed in operative contact relation with a rotatable drum 27.

The blades 28¹ to 35¹ are connected with 10 the solenoids of the four signal boxes 10 shown in Fig. 3, and the blade 36¹ is connected with the siren 20 for the purpose hereinafter specified.

Each pair of blades 28, 28¹ to 36, 36¹, inclusive, serve as switch elements and are adapted to be closed by bridge elements 28², 29², 30², 31², 32², 33², 34², 35² and 36² that engage the respective blades as the drum 27 is rotated.

20 If the drum 27 is rotated to cause contacts 28² and 29² to engage blades 28, 28¹ and 29, 29¹, respectively, the circuits of the two diagonally opposite signal boxes are thereby closed. Further rotation of the drum 27 25 will break this contact and make contact of elements 30² and 31² with blades 30, 30¹ and 31, 31¹ thus closing circuits with the other two diagonally opposite signal boxes. The two contact positions above described 30 are all that are used in the normal working of the signal apparatus to control traffic moving in four directions, but in case the drum is rotated still farther, the bridge element 36² will engage blades 36 and 36¹ thus 35 closing the siren circuit and causing the siren 20 to sound a warning before the drum can be moved into the emergency position with bridges or conductors 32², 33², 34² and 35² in engagement with blades 32, 32¹; 33, 33¹; 34, 34¹ and 35, 35¹. In the same manner a warning signal will be sounded by the siren while the drum is being moved from the emergency position back to the normal working position, the use of the siren in 45 the manner just described constituting one feature of the present improvement.

The above referred to signal devices may be of any suitable type such, for example, as are illustrated and described in my prior co-pending application, the present invention being chiefly concerned with the electric circuit connections that may be locally controlled by a traffic officer until an alarm is sent out from a central station through the agency of a master circuit for suitably operating all of the above described semaphore signals, as well as sounding the siren and illuminating a fire signal simultaneously in case of fire. This latter apparatus 50 consists in providing switch blades 40, 41, 42, 43, 44 and 45 that are adapted to be engaged by a contact bar 46 on the end of an arm 47 that is mounted on a pivot 48 and supported by a magnet bar 49 that is pivotally connected therewith and disposed

within a solenoid winding 50, one terminal of which is connected by a circuit wire 51 with one side of a battery 52 and the other terminal connected by a wire 53 with a switch 54 that is located at any distant 70 point, as in a central fire station, and is connected by wire 55 with the other side of the battery so that when the switch 54 is closed, the magnet bar 49 will be lifted by the solenoid 50 to move the contact bar 46 into engagement with the switch blades 40 to 45 inclusive.

The contact bar 46 is connected with one side of the battery B by the conductor wire 24¹, and the switch blades 40 to 44 inclusive 80 are connected with the other side of the battery B by conductor wires 57 which tap onto the conductor wires 23 adjacent the blades 32¹ to 36¹, respectively, in such manner that when the contact bar 46 engages the switch blades 40 to 44, the circuits to all of the signal boxes 10 and the circuit to the siren 20 will be closed. At the same time, the circuit to the lamp in the signal box 21 which is connected on one side by wire 58 90 with a circuit wire 23 and on the other side by wire 59 with switch blade 45, will be closed. When the above-described circuits are closed from a controlling circuit which renders the local or drum control circuit 95 temporarily inoperative and the apparatus affected so that the signal boxes 10 all display the "stop" signal, the siren sounds an audible warning, and the fire signal lamp is lighted.

At 60 I have shown as independent switch for closing the circuit to the siren 20 at the will of the traffic officer and independently of all other circuits.

From the foregoing it is apparent that the 105 traffic officer can selectively regulate the semaphore signals at the diagonally opposite corners through the instrumentality of a controller, and that said controller may also be used to regulate the signals so as to 110 stop all traffic, but before and after such all-stop or emergency signals are rendered operative, a controller automatically effects an alarm through the agency of a siren or its equivalent.

Furthermore, provision is made whereby the all-stop or emergency signals, the siren and the light signals may be simultaneously actuated from a remote place and when thus affected the aforesaid controller is caused 120 to be inoperative. These novel results are attained through the agency of the before explained instrumentalities.

What I claim and desire to secure by Letters-Patent is—

1. In apparatus of the class described, a plurality of electrically operated signals, a controller adapted to be regulated for actuating said signals either selectively or in unison, and manually controlled electrically op- 125

erated means whereby said signals are electrically actuated to the exclusion of said controller.

2. Apparatus of the class described, comprising signals, electric circuits therefor, selective switch mechanism in said circuits for actuating said signals, and another circuit having a switch operable from a central station to control said signals and render said 10 selective switch mechanism temporarily inoperable.

3. Apparatus of the class described, comprising signals, electric circuits connected therewith, selective switch mechanism for 15 closing said circuits, secondary circuits connected with said first named circuits, and electrically actuated by manually controlled means from a central station for closing said secondary circuits to operate said signals to 20 the exclusion of said selective switch mechanism.

4. Apparatus of the class described, comprising a plurality of signal devices, electro-magnets for operating said signal devices, 25 an electrical circuit for each of said electro-magnets, switch mechanism connected with said circuits to selectively energize said electromagnets, secondary circuits connected with said first named circuits, a switch for 30 closing said secondary circuits to simultaneously energize all of said electro-magnets and render said selective switch mechanism inoperative, and electrically controlled operating means for said switch.

5. Apparatus of the class described, comprising electrically operated visual signals, an electrically operated audible signal, switch mechanism for selectively operating said visual signals, said switch mechanism 40 having two normal working positions and an emergency position, and means interposed in said switch mechanism for effecting the sounding of said audible signal when said switch mechanism is moved from either of 45 said normal working positions to said emergency position.

6. Apparatus of the class described, com-

prising electrically operated visual signals, an audible signal, switch mechanism for selectively operating said visual signals, said 50 switch mechanism having normal working positions and an emergency position, devices for sounding said audible signal when said switch mechanism is moved between said normal working positions and said emergency position, and an independent switch for operating said audible signal without employing the aforesaid switch mechanism. 55

7. Apparatus of the class described, comprising a plurality of visual traffic controlling signals, an audible signal, primary circuits for the respective signals, switch mechanism to selectively operate said visual signals through the medium of the respective circuits, devices including the circuit of said 60 audible signal for causing the latter to be sounded when said switch mechanism is moved between predetermined positions, a visual fire signal, secondary circuits, and emergency switch devices adapted to be connected therewith for actuating all of said signals independently of said selective switch mechanism and render the latter temporarily 65 inoperable.

8. Apparatus of the class described, comprising visual signals, electro-magnets to operate said signals, an audible signal, electric circuits connected with said electromagnets, selective switch mechanism having a normal operative position and an emergency position, means between said two positions controlling said audible signal, a visual fire signal, secondary circuits, a switch provided therein, and electrical means operable from a central station for closing said switch to 70 render said selective switch mechanism temporarily inoperable and serving to simultaneously operate all of said signals. 75

Signed at Seattle, Washington, this 28th day of August, 1916.
